UNITED STATES PATENT OFFICE.

ANDREW J. CULP AND ALONZO W. ALLEN, OF PHILADELPHIA, PA.

WINDING-MACHINE.

SPECIFICATION forming part of Letters Patent No. 334,569, dated January 19, 1886.

Application filed December 6, 1884. Serial No. 149,636. (No model.)

To all whom it may concern:

Be it known that we, ANDREW J. CULP and ALONZO W. ALLEN, both citizens of the United States, residing in the city and county of Philadelphia, State of Pennsylvania, have invented 5 a new and useful Improvement in Winding-Machines, which improvement is fully set forth in the following specification and accompanying drawings, in which—

10 Figure 1 represents a side elevation, partly broken away, of a portion of a thread-winding machine embodying our invention. Fig. 2 represents a front view thereof, and Fig. 3 represents a view of a detached portion.

15 Similar letters of reference indicate corresponding parts in the three figures.

Our invention consists of certain improvements in machines for winding yarn or thread, as will be hereinafter fully set forth, whereby 20 the yarn may be wound with a uniform tension.

25 The devices may be used in connection with machines such as shown in the Patent No. 276,758, granted to J. and T. A. Boyd, May 1, 1883.

Referring to the drawings, A represents a 30 swift formed of two reels, one of which is mounted on a frame or upright, A', and the other on a gravitating arm, B, which is pivoted to said upright.

C represents an upright or other portion of the frame of the machine, and from the same projects a stud, D, to which is secured an angular arm, E, and on which is mounted a 35 yielding arm, G, the outer end whereof carries two rollers, H.

J represents a spring, which is connected 40 with the arm G and the upward extension F of the arm E, the tendency of which is to raise said arm G.

Pivoted to the lower end of the arm E is an arm, K, the outer end of which carries a roller, L, and connected with said arm K is a spring, M, which is also connected with the limb E' 45 of the arm E, the object whereof is the elevation of the arm K in the direction toward said limb E'.

N represents a spring-arm, which is connected at one end with a beam of the machine 50 so as to vibrate the entire length of the arm, the free end of the same carrying a roller, O.

The operation is as follows: A hank or skein is placed on the reels of the swift, and if it is drawn from the lower reel the yarn or thread is passed therefrom around one of the rollers 55 H of the swinging or vibrating arm G, then around the roller O of the spring rod or arm N, and next around the other roller H of the arm G, and finally to the bobbin or cop to be filled or formed. If the yarn is delivered 60 from the upper reel of the swift, having been placed on both reels, as in the operation just described, it is run therefrom around the roller L of the arm K, and then around one of the rollers H, down around the roller O, and finally 65 around the other roller H to the bobbin or cop. In either case the arms G and N or the arms G, K, and N either advance or retract, as may be occasioned by changes in the tension or nature of the yarn or thread, so that 70 the latter is directed to the bobbin or cop in a uniform manner and regular formation of the same is occasioned, besides which the breaking of the yarn or thread is prevented. As the arm N has a large sweep and is elastic throughout, it operates sensitively, and 75 the arms G, K, being heavier, move less sensitively, so that there is, in a measure, an equalization of action on the thread. The arms K, G are also important features, as they 80 provide in the same machine guides for running off the yarn or thread either from the upper or lower reels of the swift, as has been stated. The vibrating arm G has at its pivotal end a boss, G', which has a horizontal 85 opening to receive the stud D and vertical opening so as to embrace the portion of the arm E through which the stud passes, it being seen that the stud thus supports the arm E and forms the bearings or axis for the arm G, said arm E also supporting the vibrating arm K and forming connections for the springs J M.

The improvement herein described, as can be readily understood, is easily connected to 90 many varieties of winding-machines, thus adding to their efficiency.

Having thus described our invention, what we claim as new, and desire to secure by Letters Patent, is—

1. A feeding mechanism for a winding-machine having a swift, a yielding arm carrying

two rollers or guides located at one end thereof, an angular arm, and a second yielding arm, the latter being pivoted to the said angular arm, substantially as and for the purpose set forth.

5. The swift A, supported on upright A', in combination with the upright A', the yielding arms G and K, angular arm E E', stud D, standard C, spring-arm N, and springs J and M, substantially as and for the purpose set forth.

10. The swift A, in combination with the yielding arms G and K, having rollers or guides, angular arm E E', standard C, having 15 stud D, the yielding arm N, having roller or guide, springs J and M, and extension F, substantially as and for the purpose set forth.

20. The swift A, having the upright A', in combination with a yielding arm, N, carrying a roller, O, yielding arms G and K, having rollers or guides, standard C, having stud D, and angular arm E E', having upward extension F, spring J, secured to said extension F and arm G, and spring M, secured to said arm K 25 and part E' of said angular arm, the said arm G

being mounted on said stud D, and the said arm K being pivoted to the angular arm E E', substantially as and for the purpose set forth.

5. A feeding mechanism for a winding-machine, having a swift, A, yielding arms G K, 30 a spring-arm, N, and supports for said swift and arms, and the springs J M, substantially as and for the purpose set forth.

6. A feeding mechanism for a winding-machine, consisting of the swift A, the arms G 35 K, with guides H H and L, the spring J M, the spring-arm N, with guide O, and supports for said swift and arms, substantially as and for the purpose set forth.

7. The yielding arms G K, the angular arm 40 E E', and springs J M, in combination with the support C, and the stud D, said stud supporting the angular arm E, and forming the bearing for the arm G, substantially as and for the purpose set forth.
